DESIGN FOR A MICROSCOPE STAND

Wilhelm Maisch, Wetzlar, Germany, assignor to
Ernst Leitz, G. m. b. H., Wetzlar, Germany

Application May 19, 1937, Serial No. 69,428

Term of patent 3½ years

To all whom it may concern:

Be it known that I, Wilhelm Maisch, a citizen of Germany, residing in Wetzlar, Germany, have invented a new, original, and ornamental Design for a Microscope Stand, of which the following is a specification, reference being had to the accompanying drawing, forming part thereof.

Fig. 1 is a side view of a microscope stand showing my new design, both sides of the stand being substantially alike.

Fig. 2 is a top view of the stand.

Fig. 3 is a rear view.

Fig. 4 is a front view.

I claim:—

The ornamental design for a microscope stand as shown and described.

WILHELM MAISCH.
